NEW YORK, ASSIGNEES TO R. W. CRAMER & COMPANY, INC., OF NEW YORK, N. Y.,
A CORPORATION OF NEW YORK

MEDICATING APPARATUS

Application filed October 30, 1926. Serial No. 145,239.

This invention is a novel medicating apparatus, and relates especially to portable medicators adapted for effecting various treatments, for example as an inhalator for 5 the treatment of the respiratory passages, although the principles are applicable to the treatment of other parts, for example the ears, by means of artificially produced currents of the treating medium; and in any case the 10 treatment may be done by means of medicating vapors or gases carried by the medium or air, or may be a mere heat treatment by means of heated gas or air.

The general object of the present invention is to afford a medicator or inhalator, particularly of a portable character, which will be more efficient and convenient to use than prior known apparatus, and which will be simple, strong and durable in construction 15 and arrangement of parts. A further object is to enable the medicator to be used either for natural inhalation by the person treated, or for forced flow or injection of the heated or medicated gases or vapors, and to permit 20 ready conversion from one use to the other. Another object is to provide an improved means of applying electric heat to the air or other medium flowing through the medicator. Other and further objects and advantages of 25 the invention will be explained in the herein-after following description of illustrative embodiments thereof or will be understood to those skilled in the subject.

To the accomplishment of the aforesaid objects and advantages the present invention consists in the novel medicator, and the novel features of combination, arrangement, construction and detail herein described or illustrated.

40 In the accompanying drawings Fig. 1 is a central cross section of a portable medicator embodying the principles of the invention, adapted especially as an inhalator.

45 Fig. 2 is a right end view of the medicator shown in Fig. 1.

Fig. 3 is a combined central section and side view of the medicator shown in Figs. 1 and 2, with the section taken at right angles 50 to that of Fig. 1.

Fig. 4 is a transverse section taken on the line 4—4 of Fig. 1.

Fig. 5 is a transverse section taken on the line 5—5 of Fig. 1.

Fig. 6 is a side view of a combined apparatus, including the medicator of Figs. 1—5 in combination with certain additional elements extending the operation and utility of the invention.

Fig. 7 is an end elevation and Fig. 8 a 60 side elevation showing the delivery end of the medicator combined with an appliance adapting the same for medication of the nostrils.

Fig. 9 is a side elevation indicating the 65 medicator combined with an appliance for the treatment of the ears.

The drawings show an exterior shell or outer sleeve 10 having indented or grooved surface portions 11 to facilitate gripping, and formed with a tapered front end 12 having opposite apertures 13 for purposes to be explained. The outer shell 11 is protected from interior heat by ventilation and for this purpose an annular space 14 is provided by 70 a system of lugs 15 spacing the shell away from an interior casing or cylinder 16 which may be considered as the body of the apparatus. The front end of the hollow body 16 is apertured with air inlet holes 17 at its opposite sides in line with the apertures 13 of the 75 ventilated shell. The front end 18 of the body is thickened so as to present a tapered inner surface 19 forming a converging passage directed forwardly into a recess 20 enclosed within the forwardly extending portion or rim flange 21.

At the rear end of the body 16 is shown a stopper or block 22 preferably fitting snugly 80 within the hollow body and serving to close tightly that end against escape of air or vapor. The plug 22 has a forwardly extending flange 23 enclosing a cylindrical space arranged to receive the rear end of the heating tube to be described. The arrangement of 85 parts described permits a simple and economical assemblage and one which may readily be united into a rigid whole by means of a pin or bolt 24 extending diametrically through the outer shell 10, two of the spacing 90 100

lugs 15, the body 16 and the closing block 22, the securing pin being preferably formed in two parts screw threaded together at an interior point.

5 An annular space or passage 25 is provided within the body 16 between the body and an interior tube 26 composed preferably of metal and containing the heating means. The openings 17 in the body constituting the inlets the travel of the air is longitudinally 10 along the annular passage 25 and thence through circumferential openings 27 near the rear end of the tube 26, the travel therefrom continuing forwardly within the heating tube. The front end of the tube is slightly 15 tapered at 28 so that the tube is firmly wedged into position against the tapered surface 19 at the front, the rear end of the tube fitting within the flange 23 of the block 22 closing the 20 rear end of the body.

The heating means hereof is preferably electric and is of a novel and advantageous character, being such that the air passing forwardly through the heating tube is compelled 25 to percolate through a mass of fibrous hot material. To secure this end there is employed a resistance 30 consisting preferably of fine metallic wire wound or covered with a fibrous and refractory material such 30 as asbestos which constitutes also an electrical insulation. This heating means may be arranged substantially as shown. A length of several feet of the asbestos covered wire is looped back and forth in loops shorter 35 than the heating tube and thrust loosely into the tube so that the material is self supporting, while at the same time substantially filling the tube and compelling the traveling air to pass in intimate contact with the heated asbestos covering. The ends 31 of the resistance wire 30 are shown passed through 40 holes formed in the block 22 and fastened by winding or otherwise to a pair of spring terminals 32 adapted to be engaged and disengaged by an electric plug 33 connected with 45 a line wire 34. By this arrangement, when the terminals are connected up to the line wires, the asbestos covered resistance 30 is highly heated as is also the metal tube surrounding it. The entering air passing rearwardly is first preheated at the exterior of the heating tube and then passing inwardly travels forwardly and becomes highly heated in traveling through the fibrous resistance 50 material. The diameter and length of the resistance wire may be predetermined to avoid giving an excessive or dangerous degree of heat, and regulation may be by interposing a rheostat in the line wire. To the heating element 55 of the apparatus may be connected a thermostat regulating the temperature at a predetermined degree, for example a bimetallic thermostat which opens and closes the circuit as the temperature exceeds or falls 60 below the desired point.

While the heating tube 26 has been described as constructed of metal, preferably the other described rigid parts are constructed of a heat resisting and electric insulating character such as bakelite. Thus the shell 10, 70 the body 16 and the block 22 are preferably constructed of bakelite, while the rigid elements at the delivery end yet to be described are preferably constructed of transparent glass. 75

Thus the delivery piece 36 is preferably of glass giving sanitary qualities and inspection of the interior. This is shown in Figs. 1, 2, 3 and 6 as shaped with a conical terminus 37 constituting a mouthpiece such as conveniently to be applied to the mouth of the patient and permit the patient to inhale the heated or medicated air or gases passing through the apparatus. Inside the mouthpiece is shown a holder or vessel 38 having a 80 conical portion 39 conforming with the tapered exit of the mouthpiece 37. Medicating or filtering material may be contained in the holder 38. The body of this holder is shown as fitting snugly within the recess 20 formed 85 by the front flange or rim 21 of the body, while the mouthpiece 36 fits snugly upon the outside of the same flange 21. The material of the holder 38 is shown at its rear end as recurved at 40 into a forwardly extending 90 flange, thus providing an annular space or cup 41 adapted to receive any excess liquid and prevent it passing from the holder into the body of the medicator. The holder is 95 preferably of glass. 100

The medicating or filtering of the air or gases passing through the apparatus may be effected by means of a tampon or small roll of gauze 42 which may be thrust through the rear opening of the holder 38 and allowed 105 to expand into the condition shown in Fig. 1. The gauze may be supplied with vaporizable liquid or other treating substance either before or after insertion in the holder. It might be provided with a breakable vial of medication which will thus keep indefinitely and require only to be broken by exterior pressure before the tampon is inserted in the holder. 110

The apparatus so far described is well adapted for treatment of bronchitis or other 115 affections of the respiratory passages. It constitutes an inhalator and requires the suction of the breath at the mouthpiece to cause the circulation and medication of the treating air as described. It has been explained that the apertures 17 constitute the 120 air inlets to the annular heating passage 25 and it will be observed that the apertures 13 in the outer shell 10 are in alinement therewith. The air therefore will pass through the apertures 13 and then the apertures 17 into the interior heating passages. The inward travel of air between the apertures 13 and 17 will tend to induce a lateral current or suction which will draw air forwardly 125 130

through the ventilating space or passage 14 separating the body 16 and the outer shell 10, and thus tending to keep cool the outer shell and rendering it possible to handle comfortably in spite of the heat developed in the interior of the apparatus.

When it is desired to use the medicator for other purposes than as an inhalator it is necessary to provide for a forced draft or passage of the treating air or gases. For this purpose the combined arrangement shown in Figs. 6 to 9 may be employed. It is one of the advantages of the present invention that it may be readily converted from an inhalator to a forced draft apparatus; and the forced draft features are also useful in treating respiratory passages of a child or person incompetent to employ the apparatus as an inhalator. The additional apparatus for converting the inhalator as explained is shown as comprising a pair of nipples 44 adapted to be thrust oppositely through the openings 13 in the shell and into tight engagement with the apertures 17 in the body, as indicated in the broken away portion of Fig. 6. The opposite nipples 44 are shown connected by separate flexible tubes 45 to a Y-connection 46 which in turn is connected by a flexible tube 47 to a suitable air forcing apparatus. This is preferably a manual apparatus comprising a pump in the nature of a bulb 48 operated by the grip of the hand, preferably combined with an elastic inflatable bulb 49 containing a one-way valve 50 at the air inlet. By this arrangement successive pressures upon the operating bulb 48 will cause the inflation of the bulb 49 and a steady pressure and flow of air through the passages 47 and 45 and thence through the apertures 17 into the body of the medicator as already described.

The form of apparatus shown in Fig. 6 is readily adaptable for various uses, for example for treatment of the nose passages by replacing the delivery piece 36 with an attachment or appliance 52 shown in Figs. 7 and 8 having terminals 53 fitting the nostrils. Another useful employment of the invention is for the treatment of the passages of the ear and for this purpose the appliance 55 shown in Fig. 9 may be employed, the same having an extension 56 adapted to be inserted exteriorly into the ear, while the medicating medium is forced through the same by the manual pumping means 48.

There has thus been described a medicating apparatus adapted for various purposes and embodying the principles of the present invention. Since various matters of combination, arrangement, construction and detail may be considerably modified without departing from the principles of the invention it is not intended to limit the invention

to such matters except so far as set forth in the appended claims.

What is claimed is:

1. A portable medicator comprising a tubular body with a head at the front end of the body, an interior heating tube spaced from the body and forming between them an annular passage for preheating of air, said head supporting and spacing the front end of the heating tube and having an annular flange extending forwardly beyond such front end of the heating tube, said body having apertures admitting air to the front end of the annular passage and said heating tube having apertures leading from said passage into the rear end of the heating tube, electrical heating means in the heating space within the heating tube, a delivery piece detachably connected to the forward flange of said head to enclose therewith a medicating chamber receiving heated air from the heating tube, and a tubular tampon holder laterally unperforated and enclosed in said medicating chamber, with its rear end fitted within the flange of said head and interiorly cupped to confine excess liquid against access to the heating space.

2. A portable medicator comprising a tubular body, an interior heating tube spaced from the body and forming between them an annular passage for preheating of air, a head spacing the front ends of the tubular body and heating tube and having an annular flange extending forwardly beyond such front end of the heating tube, said body having apertures admitting air to the front end of the annular passage and said heating tube having apertures leading from said passage into the rear end of the heating tube, heating means within the heating tube, a delivery piece detachably connected to the forward flange of said head to enclose therewith a medicating chamber receiving heated air from the heating tube, and a tubular tampon holder enclosed in said medicating chamber, with its rear end fitted within the flange of said head and cupped to confine excess liquid against access to the heating space.

3. A portable medicator comprising a tubular body with a head at the front end of the body, an interior heating tube spaced from the body and forming between them an annular passage for preheating of air, said head supporting and spacing the front end of the heating tube and having an annular flange extending forwardly beyond such front end of the heating tube, said body having apertures admitting air to the front end of the annular passage and said heating tube having apertures leading from said passage into the rear end of the heating tube, electrical heating means in the heating space within the heating tube, a delivery piece detachably connected to the forward flange of said head to enclose therewith a medicating chamber

receiving heated air from the heating tube and adapted to receive a tampon holder, an exterior shell enclosing the tubular body but spaced outwards thereof leaving a ventilating passage extending longitudinally and open at both ends, and lugs spaced from each other and spacing said body and shell from each other to leave such ventilating passage, and the front end air admitting 10 apertures of said body being arranged to receive outside air direct and to take air from said ventilating passage only by induced draft.

15 In testimony whereof, we have affixed our signatures hereto.
